(57) **CLAIM**

The ornamental design for a mount for boat, as shown and described.

DESCRIPTION

FIG. 1 is a top, front, right side perspective view of a mount for boat;

FIG. 2 is a top, rear, right side perspective view thereof;

FIG. 3 is a bottom, rear, right side perspective view thereof;

FIG. 4 is a bottom, front, left side perspective view thereof;

FIG. 5 is a front elevation view thereof;

FIG. 6 is a back elevation view thereof;

FIG. 7 is a top plan view thereof;

FIG. 8 is a bottom plan view thereof;

FIG. 9 is a left elevation view thereof; and,

FIG. 10 is a right elevation view thereof.

The broken lines illustrating portions of the mount for boat form no part of the claimed design.
